DESIGN FOR A COMBINED PERFUME BOTTLE AND SACHET PADS DISPLAY, AND TRANSPARENT CONTAINER THEREFOR

Florence Samuels, New York, N. Y.

Application December 15, 1939, Serial No. 88,917

Term of patent 3½ years

To all whom it may concern:

Be it known that I, Florence Samuels, a citizen of the United States of America, residing in New York city, in the Borough of Manhattan, county and State of New York, have invented a new, original, and ornamental Design for a Combined Perfume Boottle and Sachet Pads Display, and Transparent Container Therefor, of which the following is a specification, reference being had to the accompanying drawing, forming part thereof, wherein,

Figure 1 is an elevational view of a combined perfume bottle and sachet pads display, and transparent container therefor, showing my design;

I claim:

The ornamental design for a combined perfume bottle and sachet pads display, and transparent container therefor, substantially as shown and described.

FLORENCE SAMUELS.
